UNITED STATES PATENT OFFICE

HARRY H. RICHMOND, OF PORTLAND, OREGON, ASSIGNOR TO ELECTRIC STEEL FOUNDRY COMPANY, OF PORTLAND, OREGON

LOGGING VEHICLE

Application filed August 6, 1929. Serial No. 383,970.

This invention relates generally to the logging industry, and particularly to logging vehicles.

The main object of this invention is to construct a logging vehicle of the high arch type in a manner which will permit the use of lighter sections than are otherwise necessary.

The second object is to employ steel castings for the purpose of eliminating expensive and uncertain welding operations.

The third object is to provide a special form of joint or connection between the various frame elements.

The fourth object is to facilitate the assembly of the elements, as well as taking same apart for shipping or storage purposes.

The fifth object is to provide a connection between the high arch vehicle and its hauling tongue which will permit a change in the relation of the arch and its prime mover by the mere substitution of a different shaped hauling tongue.

The sixth object is to so construct the vehicle as to make it possible to better control the dimensions thereof by putting it in a form which better adapts itself to casting methods.

The seventh object is to facilitate the assembling of the vehicle in the field.

The eighth object is to provide an additional reinforcement for the connecting means in the form of a through bolt.

These, and other objects, will become more apparent from the specification following as illustrated in the accompanying drawings in which:

Figure 1 is a plan of the vehicle showing the method of attaching same to a tractor.

Figure 2 is a side elevation of the vehicle as shown in Fig. 1.

Figure 3 is a vertical section along the line 3—3 in Fig. 2.

Figure 4 is a section taken along the line 4—4 in Fig. 2.

Figure 5 is a plan of one side of the tongue.

Figure 6 is a side elevation of the tongue side shown in Fig. 5.

Figure 7 is a section along the line 7—7 in Figure 2.

Figure 8 is a section along the line 8—8 in Fig. 5.

Figure 9 is a section along the line 9—9 in Fig. 5.

Figure 10 is a plan of the neck with parts 55 broken away in section.

Figure 11 is a side elevation of the neck with a part broken away in section.

Figure 12 is a section along the line 12—12 in Fig. 2.

Similar numbers of reference refer to similar parts throughout the several views.

Referring in detail to the drawings, there is shown a vehicle consisting of a pair of spaced crawler type of trailing elements 15 which are pivotally attached by means of the pins 16 between the forked ends 17. The tongue portion 18 is attached to the forked ends 17 by means of the pins 18—A. The forward ends 19 of the tongue sections 18 are flanged and provided with a pair of projecting lugs 20 which fit into the recesses 21 of the body 22 of the neck 23, whose middle portion is bent (as shown) for reasons which will be better understood from what follows. 75

The head 24 is provided with an opening 25 which receives the shank 26 of the ball 27 which fits into the socket 28 mounted on the frame 29 of a cable winding hoist which is provided with a drum 30 upon which is wound a cable 31. The shank 26 is held in position by a nut 32. The ball 27 is held in the socket 28 by means of a cover plate 33 which is held in position by means of the bolts 34. The flanges 19 are held against 85 the flanges 35 of the body 22 by means of the bolts 36, which could of course extend entirely across the body 22 if desired. The lugs 20 are somewhat tapered and fit closely against the sides of the recesses 21 making a rigid connection when the bolts 36 are pulled up tight. It is also desirous to provide a continuous hole 37 through the flanges 19 and the body 22 for the bolt 38, which may be employed as an additional 95 means for uniting the parts of the vehicle.

It will be noted in Figures 8 and 9 that the tongue 18 is somewhat square in cross section and hollow, giving the maximum strength for a given weight. 100

It is desirable to employ a tractor 39 of the crawling or track laying type, on which the frame 29 of the hoist is mounted.

The arch 40 of the vehicle is also of a cast section and its forked ends 17 are attached to the pins 16 of the trailing elements 15, as previously described. On top of the arch 40 is mounted a horizontal roll 41 behind which is a pair of spaced vertical rolls 42 between which, and over the roll 41, the cable 31 passes to the choker hooks 43 by means of which they are secured around the logs 44.

Between the forward ends of the tongue 18 and the upper portions of the arch 40 are the tie members 45 preferably provided with a plurality of holes 46, by means of which the length of the tie 45 may be varied for the purpose of changing the angular relation between the arch 40 and the tongue 18. This connection is shown in Figure 4.

It can thus be seen that the upright position of the arch 40 can be varied at will as may be found necessary, due to the varying conditions under which the logging is being done, such as contour of the ground, size of logs and height of hitch or connection to the tractor itself. It can also be seen that by varying the shape of the neck 23 the vehicle may be made to adapt itself to a wide range of tractor mountings. In other words, where the hitch is lowered, as it might be on some tractors, a neck of greater curvature should be provided for the purpose of allowing a small amount of clearance for the ends of the logs 44.

I claim:

1. A logging vehicle consisting of a pair of forked tongue members sloping upwardly towards the forward end, a neck joining the forward ends of said tongue, an arch spanning said forked ends and hingedly connected thereto, brace means between said arch and tongue and ground engaging elements supporting the opposite sides of said arch.

2. In a logging vehicle the combination of a pair of ground engaging elements, a forked tongue extending from each of said elements sloping forwardly and upwardly toward each other, a downwardly curved neck constituting a hitch forming a means for uniting said curved tongue ends into a rigid structure, an arched frame having its ends hingedly mounted above said ground engaging elements, said arched frame having fair loading rolls at the top thereof, and brace means for maintaining the relation between said arch and tongue means.

3. In a logging vehicle the combination of a pair of ground engaging elements of the crawler type, a high arch frame spanning said crawler elements and hingedly connected to each of same, a tongue hinged to the foot of each side of said high arch frame extending upwardly, forwardly and inwardly toward each other, an adjustable brace

between said high arch frame and tongue, and a downwardly curved neck forming a means for uniting the forward ends of said tongue members and for flexibly uniting same to a tractor.

4. In a logging vehicle the combination of a pair of spaced forked tongue members having their forward ends curved toward each other, the adjacent faces thereof having projecting lugs formed thereon, a curved neck between said adjacent tongue ends having recesses therein adapted to receive said lugs, and a ball and socket connection at the forward end of said neck for attaching same to a tractor.

5. In a high arch vehicle the combination of a pair of ground engaging elements having an upright U-shaped arch and a forwardly and upwardly sloping U-shaped tongue attached thereto at the open ends thereof by means of a hinge connection, and brace means for holding said upright arch and sloping tongue in a desired relation.

6. In a high arch vehicle the combination of a pair of laterally spaced ground engaging elements of the crawler type, an upright arched frame having each open end thereof forked to straddle said ground engaging elements and having a pivotal connection thereto, a U-shaped tongue sloping upwardly and forwardly having its open ends forked and hingedly attached to the lower ends of said arch frame, adjustable brace means between said tongue and frame, and a downwardly curved neck having means for bolting same at the forward end of said tongue, said neck having a universal connection thereon.

HARRY H. RICHMOND.
